US00D897100S

(12) **United States Design Patent** (10) **Patent No.:** **US D897,100 S**
(45) **Date of Patent:** **** Sep. 29, 2020**

(54) **CASE FOR GAME DEVICE**

(71) Applicant: **Shenzhen Tomtoc Technology Co., Ltd.**, Guangdong (CN)

(72) Inventor: **Zhuo Liu**, Changsha (CN)

(**) Term: **15 Years**

(21) Appl. No.: **29/654,083**

(22) Filed: **Jun. 21, 2018**

(51) **LOC (12) Cl.** **03-01**

(52) **U.S. Cl.**

USPC **D3/276**; D3/269; D3/273

(57) **CLAIM**

The ornamental design for a case for game device, as shown and described.

DESCRIPTION

FIG. 1 is a perspective view of a case for game device showing my new design

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines shown in the Figures form no part of the claimed design.

1 Claim, 7 Drawing Sheets

FIG. 1

FIG. 2

FIG. 3

FIG. 4

FIG. 5

FIG. 6

FIG. 7
